UNITED STATES PATENT OFFICE.

WILLIAM H. LLOYD, OF BROOKLINE, MASSACHUSETTS, ASSIGNOR TO THE SMITH & ANTHONY COMPANY, OF BOSTON, MASSACHUSETTS.

URINAL.

SPECIFICATION forming part of Letters Patent No. 628,205, dated July 4, 1899.

Application filed March 30, 1898. Serial No. 675,670. (No model.)

To all whom it may concern:

Be it known that I, WILLIAM H. LLOYD, of Brookline, in the county of Norfolk and State of Massachusetts, have invented certain new and useful Improvements in Urinals, of which the following is a specification.

This invention has for its object to provide a urinal embodying a receiving-bowl, an outlet therefor adapted for attachment to a discharge-pipe, a trap adapted to hold a body of water in position to seal the outlet, and means for changing the water in the said trap, so that urine will not stand therein long enough to create a nuisance.

15 The invention consists in the novel features of construction and relative arrangement of parts hereinafter fully described in the specification, clearly illustrated in the drawings, and particularly pointed out in the claim.

20 Of the accompanying drawings, forming a part of this specification, Figure 1 represents a front elevation of a urinal embodying my invention. Fig. 2 represents a section on line 2 2 of Fig. 1. Fig. 3 represents a section on line 3 3 of Fig. 2.

25 The same letters and numerals of reference indicate the same parts in all the figures.

My improved urinal comprises a bowl having an enlarged front opening, the lower edge 2 of which is raised above the bottom 3 of the bowl. The back wall 4 of the bowl extends below the lower edge 2 of the front opening. An outlet-passage 5 extends upwardly from the bottom of the bowl behind the back wall 35 4 and above the lower end 9 thereof and communicates with a downwardly-extending passage 6, which terminates in a horizontal neck 7. Said neck projects from the back of the bowl far enough to be connected with a discharge-pipe 6. The bowl, back, and outlet-passage 5 form a trap adapted to retain a body of water in position to seal the outlet-passage, as shown in Fig. 2. The passages 5 6 are arranged to form a siphon, of which the passage 45 6 is the longer leg, the same extending below the lowest portion of the passage 5, so that the siphon will act to draw water from the bowl until the water-line is below the point 9.

Behind the back wall 4 is a water-receiving chamber 8, the upper end of which communicates with the supply-pipe 6, which delivers

water to the bowl, the arrangement shown in the drawings being such that a part of the water delivered by the pipe 6 enters the tubular rim 4 of the bowl and flows down the inner sides of the bowl, while a part enters the chamber 8. The upper portion of the said chamber is enlarged, as shown in Fig. 3, so that it is adapted to hold a considerable quantity of water. From the lower portion 55 of the chamber 8 extends a contracted outlet 6, which discharges a small stream into the lower portion of the bowl, preferably at the junction of the outlet-passage 5 with the bowl.

Beside the upper portion of the chamber 8 65 is a retarding-chamber 80, which communicates with the chamber 8 through orifices 19 and 20 in a partition 18 between the two chambers. The retarding-chamber is adapted to contain enough water to fill the trap, or 70 substantially so, and said chamber is filled with water from the chamber 8 during the flushing discharge. The said discharge is usually sufficient to more than fill the chamber 8, the water accumulating therein faster 75 than it escapes through the contracted outlet 6, so that the chamber 80 is filled before the water can subside from the chamber 8.

It will be seen that the chamber 8 is extended vertically to a considerable height 80 above the trap, and therefore holds a column of water, which is discharged into the trap with sufficient force to cause an effective removal of the contents of the trap, an outward flow through the passage 5 being induced by 85 the jet discharged from the chamber 8. After the flow from the chamber 8 has ceased the retarding-chamber 80 continues to discharge water into the trap, the capacity of the retarding-chamber and the rate of discharge 90 therefrom being such that enough water flows from the retarding-chamber after the flushing flow has ceased and after the described action of the siphon to displace the water left in the trap, and thus insure the complete removal of the urine therein, the trap being filled by the pure water discharged from the chamber 80. The bowl is thus kept clean, and 95 deposits on its surface from the urine are prevented.

100 The location of the contracted outlet 6 so as to discharge directly into the bottom of

the trap and in a direction toward the uptake 5 of the siphon is a material factor in this keeping of the bowl clean, for it insures that nothing whatever uncleanly shall be left at the 10 bottom of the bowl either during the flushing operation or afterward while the chamber 80 is being emptied.

I do not limit myself to the form and arrangement of the retarding-chamber here 15 shown, and the same may be variously modified without departing from the spirit of my invention.

To enable obstructions to be removed from the outlet *e*, I provide a clean-out nipple *h*, 15 having an orifice *h'* extending to the outlet *e*. Said orifice is closed by a removable screw.

It will be seen that the water-receiving chamber 8 extends above the trap in a substantially vertical plane from the point of 20 discharge from said chamber to the bowl and that the passage for the water through the chamber 8 to the contracted outlet communicating with the bottom of the trap is a substantially straight one, and hence offers the 25 least resistance to the passage of water therethrough and also occupies the minimum amount of space at the rear of the bowl of the urinal. It will also be seen that the retarding-chamber 80 is located at one side of the

chamber 8 and in the same plane therewith, 30 thus providing a reservoir for water, so as to fill the trap, as heretofore described, without requiring the setting of the bowl forward in order to accommodate the retarding-chamber at the rear. In other words, the receiving-chamber and the retarding-chamber are in one plane or side by side at the rear of the bowl. 35

I claim—

A urinal having a trap at its lower portion, 40 a water-receiving chamber 8 extending from the upper to the lower portion of the bowl and arranged to receive water at its upper end from a supply-pipe connected with the bowl, its lower end discharging into the bottom of the trap, and a retarding-chamber 80 located above the trap and communicating with the chamber 8, and having a capacity substantially equal to that of the trap, the 45 said receiving-chamber 8 and retarding-chamber 80 being located in one plane or side by side at the rear of the bowl.

In testimony whereof I affix my signature in presence of two witnesses.

WILLIAM H. LLOYD.
